(57) **CLAIM**

The ornamental design for a shoe fastener, as shown and described.

DESCRIPTION

FIG. 1 is an isometric view of a shoe fastener, showing my new design.

FIG. 2 is another isometric view thereof, shown in closed condition.

FIG. 3 is a top plan view thereof.

FIG. 4 is a bottom plan view thereof.

FIG. 5 is a right side elevation view thereof, and the left side view being a mirror image thereof.

FIG. 6 is a front elevation view thereof, and the rear view being a mirror image thereof; and,

FIG. 7 is a top perspective view thereof, shown in environmental use.

The broken line portions of FIG. 7 are included to show environmental use only and form no part of the claimed design.
